UNITED STATES PATENT OFFICE

2,496,945

THREAD RETAINER AND SAVER

Alfred Hudson Johnson, Downey, Calif.

Application November 12, 1947, Serial No. 785,412

6 Claims. (Cl. 242—126)

1

The present invention relates to an attachment for a spool of thread, the attachment being such that it serves to grip the free end of the thread in a manner to prevent same from uncoiling from the spool, whereby to conveniently save thread and to minimize annoyances attending the unreeeling of the thread end, especially if and when the spool is accidentally dropped on the floor or elsewhere.

Needless to say, and as the introductory statement of the invention implies, I am sufficiently conversant with the prior state of the art to recognize that all sorts of spool attachments have been adopted and used by competitors and rival inventors, including shields, protectors, thread-end gripping devices and holders, and the like. Therefore, in carrying out the principles of the present invention, I have evolved and produced a simple and expedient attachment which is in the nature of a spring metal yoke, the limbs of the yoke engaging over the ends or heads of the spool, and the intermediate or bight portions being constructed to provide the desired clamping or gripping action for the free end of the thread. More explicitly, in carrying out the principles of the invention I provide a substantially U-shaped resilient metal strap which has a return bend, the latter being substantially L-shaped and the U-shaped and L-shaped portions being joined by spring means which provides the necessary tension between parts so that the thread accommodation apertures in the respective coacting parts are normally held out of alignment to grip and hold the thread, but may be, by slight pressure, moved into alignment, to permit the thread to be freely pulled therethrough for threading needles and the like.

Other objects, features and advantages will become more readily apparent from the following description and the accompanying illustrative drawings.

In the drawings, wherein like numerals are employed to designate like parts throughout the same:

Figure 1 is a perspective view of a conventional spool of cotton, with the thread saver attachment in place thereon.

Figure 2 is a central vertical sectional view through the structure seen in Figure 1.

Figure 3 is a horizontal section on the plane of the line 3—3 of Figure 1, looking in the direction of the arrows.

Figure 4 is a fragmentary perspective view showing coacting bayonet-slots and complementary notch forming self-threading means and ill-

2

lustrating the initial handling of the free end of the thread.

Figure 5 is a corresponding perspective showing the next and final threading steps.

Figure 6 is a fragmentary perspective with the relatively shiftable limbs separated to better disclose the pilot notch and bayonet slots.

Referring now to the drawings by distinguishing reference numerals, the spool, which is conventional, is denoted by the numeral 5, and includes the usual central bore 6. The cotton or thread 7 is wound on the spool and the free end, the end which is to be releasably gripped and held against displacement, is denoted by the numeral 8.

The attachment, as before stated, is formed from resilient strap metal. There is one section of the metal which is of U-shaped form and this is denoted by the numeral 9 and comprises a limb 10 having an offset bend 11 at one end which fits into the adjacent end of the bore 6 and serves to clamp this end of the device on the spool. There is a similar laterally bent end portion or limb 12 at the opposite end of the spool which has a bend 13 fitting into said bore 6, whereby this end of the U-shaped part 9 is releasably held in place.

The connective or bight portion of said U-shaped part is denoted by the numeral 14. The other unitary portion of the device is L-shaped as before indicated and is here denoted by the numeral 16 and is fashioned from the same length of strap metal. That is to say, the lower limb 17 is integrally joined with the limb 12 by way of the adaptor 13, the latter part serving not only as an assembling element but a spring as well.

The limb 17 is bent, as at 18, to provide the final and remaining limb 19, which is in slidable contact with the limb 14. The extremity of the limb 19 is bent laterally as at 20, to provide a tang and this is operable in a slot 21 in the limb 10, in the manner shown. It will be noticed that the shiftable limb 19 is provided with assembling hooks 22 and 23, which take over and thus slidably assemble the respective limb portions 14 and 19.

In addition, the limb 19 is provided with an outstruck tongue 24, which, if desired, may be used as a thread cutter.

It will be evident from the description, so far given, in conjunction with the drawings that the attachment, structurally visualized is a U-shaped frame and is readily applicable and removable. What is more important, the intermediate overlapping portions of the relatively shiftable limbs 14 and 19 are especially constructed with aperture means to frictionally grip the free end of

the thread, to allow it to be released and pulled when unspooling and frictionally gripped and held against unwinding when the spool is not in use. In addition, the aperture means is such that it is virtually self-threading. Reference is had first to Figure 6 wherein it will be seen that there are two bayonet slots. The slot in the limb 14 is denoted by the numeral 25, the entrance edge 26 being registerable with a pilot notch 27. The finger portion of the notch is denoted at 28 and the crotch portion at 29. Arranged in somewhat reverse order is a bayonet slot 30 in the other shiftable limb 19 whose finger portion is denoted by the numeral 31 and whose crotch portion is at 32. Normally the spring action of the limbs brings the respective crotch portions 29 and 32 into the positions shown for example in Figures 1, 2 and 4. At this time said crotch portions are formed, between themselves, a so-called thread hole in which the thread is frictionally gripped and held against slippage. Thus, the slots act primarily to grip the thread but may be shifted in relation to each other when the attachment is squeezed to move the crotch portions 29 and 32 away from each other sufficiently far to allow the thread to be freely drawn through said hole. When the thread is initially placed in position it is seated in the pilot notch 27 and then fed down over the entrance edge 26 into the mouth portion of the slot 25 where it is guided by the finger 28, after which it is drawn between the two limbs 14 and 19 in the manner shown. This first step is illustrated in Figure 4 and the second step we see in Figure 5 wherein the thread is being drawn between the two parts 14 and 19 and is about ready to be hooked around and over the finger 31 to enter the slot 30. In fact, the third step is seen in Figure 5 wherein the thread has entered the slot 30 and is drawn into the crotch portion 32 where it is then threaded through the thread hole made up by the co-acting crotch portions of the respective slots. To release the thread the movements seen in Figures 5 and 4 respectively are reversed.

The invention is relatively simple and for this reason it is believed not altogether necessary to dwell at great length upon the details of construction, for these phases are clear from the drawings.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention what is claimed as new is:

1. A spool attachment of the class shown and described comprising a resilient one-piece U-shaped member embodying a central bight portion and laterally disposed flexible end portions terminating in attaching and retaining adapters designed, when in position for use, to project into co-acting end portions of the usual bore of a spool, said bight portion having a thread-end receiving and gripping slot opening at one end and extending laterally through one longitudinal edge of said bight portion, a latch forming limb superimposed upon and slidably con-

nected to said bight portion, said limb also having a thread-end receiving and gripping slot in registry with said first named slot and opening at one end and extending laterally through a longitudinal edge of said limb, said limb having a finger-piece at one end for manually sliding the limb and shifting the slots in relation to each other, and spring means between and connected with said U-shaped member and finger-piece, said spring means serving to retain said limb normally in a position to sustain said slots in thread gripping relationship.

2. A spool attachment of the class shown and described comprising a resilient one-piece U-shaped member embodying a central bight portion and laterally disposed flexible end portions terminating in attaching and retaining adapters designed, when in position for use, to project into co-acting end portions of the usual bore of a spool, said bight portion having a thread-end receiving and gripping slot opening at one end and extending laterally through one longitudinal edge of said bight portion, a latch forming limb superimposed upon and slidably connected to said bight portion, said limb also having a thread-end receiving and gripping slot in registry with said first named slot and opening at one end and extending laterally through a longitudinal edge of said limb, said limb having a finger-piece at one end for manually sliding the limb and shifting the slots in relation to each other, said finger-piece being at right angles to said latch limb, spaced from and parallel to the adjacent lateral end portion of said U-shaped member, and spring means joining said finger-piece to said lateral end portion, whereby said limb is normally sustained in a position wherein corresponding closed end portions only of said slots overlap and serve to frictionally grip said thread-end.

3. The structure defined in claim 1, wherein that edge of the limb through which the second named slot opens is provided with a thread-end placement and guiding notch, the latter being normally in registry with the open end of the first named slot.

4. A spool attachment of the class shown and described comprising a resilient one-piece U-shaped member embodying a central bight portion and laterally disposed flexible end portions terminating in attaching and retaining adapters designed, when in position for use, to project into co-acting end portions of the usual bore of a spool, said bight portion being provided intermediate its ends with a bayonet slot with its open end opening laterally through one longitudinal edge of said bight portion, a latch forming limb superimposed upon and slidably joined to said bight portion and provided at one end with a thread cutter, at its opposite end with a lateral finger-piece opposed to and spaced in parallelism to the corresponding lateral end portion of said U-shaped member and having spring connection with said lateral end portion, said limb also having a centrally located bayonet slot whose open end opens laterally through a longitudinal edge of the limb, the respective closed ends of said bayonet slots being normally in registry with each other, and said longitudinal edge of the limb having a thread-end receiving and piloting notch in registry with the open end of said first named bayonet slot.

5. A spool attachment of the class shown and described comprising a one-piece structural assemblage fashioned from a single length of strap

metal, one end portion of said strap being bent upon itself and providing a readily applicable and removable U-shaped member, the other end portion being bent upon itself to provide an L-shaped member, said U-shaped member embodying a central bight portion and lateral end portions, one end portion terminating in a bend which is laterally offset and functions as an adapter to fit into an end portion of the bore of a spool, the other lateral end portion terminating in an offset bend and said bend constituting an adapter to fit into said bore and also functioning as a yieldable spring, the short limb of said L-shaped member being attached to said spring and disposed in spaced parallelism in relation to the adjacent end portion of the U-shaped member, the longer limb being disposed in overlapping relation with the bight portion and being slidably connected to said bight portion, said bight portion and longer limb having registerable apertures for passage of a free end portion of the thread on said spool.

6. A spool attachment of the class shown and described comprising a one-piece structural assemblage fashioned from a single length of strap metal, one end portion of said strap being bent upon itself and providing a readily applicable and removable U-shaped member, the other end portion being bent upon itself to provide an L-shaped member, said U-shaped member embodying a central bight portion and lateral end portions, one end portion terminating in a bend which is laterally offset and functions as an adapter to fit into an end portion of the bore

20 of a spool, the other lateral end portion terminating in an offset bend and said bend constituting an adapter to fit into said bore and also functioning as a yieldable spring, the short limb of said L-shaped member being attached to said spring and disposed in spaced parallelism in relation to the adjacent end portion of the U-shaped member, the longer limb being disposed in overlapping relation with the bight portion and being slidably connected to said bight portion, said bight portion and longer limb having registerable apertures for passage of a free end portion of the thread on said spool, the first-named lateral end portion of said U-shaped member being provided with a slot, the adjacent free end portion of said longer limb being provided with a laterally bent tang keyed for operation in said slot.
